UNITED STATES PATENT OFFICE.

THOMAS SCOTT HAMILTON, OF KING CITY, CALIFORNIA; W. J. HAMILTON AND GEO. W. HAMILTON EXECUTORS OF SAID THOMAS S. HAMILTON, DECEASED.

SCARF-HOLDING COLLAR ATTACHMENT.

1,193,505.

Specification of Letters Patent. Patented July 14, 1914.

Application filed May 31, 1912. Serial No. 700,608.

To all whom it may concern:

Be it known that I, THOMAS S. HAMILTON, a citizen of the United States, residing at King City, in the county of Monterey and State of California, have invented new and useful Improvements in Scarf-Holding Collar Attachments, of which the following is a specification.

This invention relates to an attachment for collars, which is especially adapted to retain the scarf or tie in proper position to allow it to move freely until the tie has been adjusted, and for attaching the collar to the back of the neckband of the shirt.

It is the object of my invention to provide an attachment which is especially applicable for collars of the turn-down type, by means of which the outer overhanging portion of the collar will be spaced from the inner portion thereof so as to allow the scarf or tie to be easily moved longitudinally therebetween, and which will prevent the scarf or tie from dropping below the overhanging part of the collar at the back thereof.

The invention consists of the parts and the construction and combination of parts as hereinafter more fully described and claimed having reference to the accompanying drawings, in which—

Fig. 1 is a perspective view of a collar, showing the attachment as applied. Fig. 2 is a vertical section on the line X—X of Fig. 1, showing the flap before being folded. Fig. 3 is a detail, vertical section on line X—X. Fig. 4, showing the collar attached to a shirt band. Fig. 5 is a vertical section showing a modification. Fig. 6 is a detail, perspective view of the attachment formed of a semi-rigid material.

In the drawings, 2 represents the inner or band portion of a collar; and 3 indicates the outer turn-down portion, between which portions 2 and 3 a scarf or tie 4 is rove in the usual manner.

The present invention resides in attaching a pair of flaps 5—6, of any suitable length, to the lower edge of the band portion 2 at the center of the back of the collar. The flaps 5—6 may be formed of the same material as that of the collar, but may be made of any semi-rigid material, the flaps 5—6 being, here shown as sewed or stitched to the band portion 2.

The flap 5 is substantially rectangular in outline and is designed to extend upwardly

between the collar portions 2—3, approximately half the height thereof; the scarf or tie 4 being passed between the flap and the band portion 2 of the collar, as shown in Fig. 3, above a shoulder formed by offsetting the upper end of the flap. The offset portion of the flap 5 serves as a separator for spacing the turn-down portion 3 of the collar from the band portion 2 and acts to insure a free movement of the scarf 4 therebetween. The flap 6 extends upwardly on the inner face of the collar portion 2 in the form of a hook, and is designed to be inserted into the pocket formed on the neckband of the ordinary shirt for the reception of a collar-button; the flap 6 forming a means for attaching the collar to the rear of the neck-band and thereby doing away with the use of buttons or other forms of engagement at this point. The flap 6 is offset adjacent to its juncture with the flap 5 to allow its ready insertion under the neck-band of the shirt and perforations are formed in the flap to facilitate its being stitched to the lower edge of the collar.

It will now be seen that when the collar is placed around the neck and secured to the neck-band of the shirt, by means of the flap 6 at the back and the usual button in front, that the scarf or tie 4 may be freely moved longitudinally between the collar portions 2—3, for the reason that the flap 5 will act to hold the outer or overhanging portion 3 of the collar away from the inner band portion 2 so that the portions 2—3 will not be drawn together and thereby pinch or bind the scarf or tie 4 therebetween.

It will be observed, by referring to Fig. 3, that the scarf or tie 4 will be prevented from falling below the overhanging portion 3 of the collar; the flap 5 forming a flange or groove and acting as a stop to limit its downward movement.

If desired the flaps 5—6 may be formed integral in one piece and set astride the lower edge of the inner band portion of the collar, as in Fig. 5.

While I have shown the attachment as applied to a turn-down collar, it is manifest that it is equally applicable for use on straight collars, as in Fig. 4.

Having thus described my invention, what I claim and desire to secure by Letters Patent is—

The combination of a collar attachment

and scarf holder comprising a plate of semi-rigid material bent upon itself at a point substantially adjacent one end to form two upstanding flaps of different lengths; the longer of said flaps adapted to fit within the collar extending upwardly a short distance, and then outwardly and upwardly away from the other flap to form a tie receiving portion, and the shorter of said flaps being curved outwardly to receive the band of the shirt, said plate being provided on either

side of said first mentioned bend with a series of openings for the reception of fastening material.

In testimony whereof I have hereunto set my hand in the presence of two subscribing witnesses.

THOMAS SCOT HAMILTON.
